(57) **CLAIM**

We claim the ornamental design for a needle support device, as shown and described.

DESCRIPTION

FIG. 1 is a top left isometric view of a needle support device illustrating a belt in dashed lines for environment.

FIG. 2 is a top left isometric view of the needle support device of FIG. 1.

FIG. 3 is a bottom isometric view of the needle support device of FIG. 1.

FIG. 4 is a left-side elevation view of the needle support device of FIG. 1.

FIG. 5 is a right-side elevation view of the needle support device of FIG. 1.

FIG. 6 is a rear elevation view of the needle support device of FIG. 1.

FIG. 7 is a front elevation view of the needle support device of FIG. 1.

FIG. 8 is a top plan view of the needle support device of FIG. 1; and,

FIG. 9 is a bottom plan view of the needle support device of FIG. 1.

The broken lines showing perforations in FIGS. 1, 2, and 4-8 represent the bounds of the claim, while the broken lines showing a belt in FIG. 1 are directed to environment. The broken lines form no part of the claimed design.
